UNITED STATES PATENT OFFICE

103,900

DESIGN FOR A TEXTILE FABRIC

Nathan Tillman, Brooklyn, N. Y.

Application March 1, 1937, Serial No. 67,923

Term of patent 3½ years

To all whom it may concern:

Be it known that I, Nathan Tillman, a citizen of the United States, residing in Brooklyn, county of Kings, and State of New York, have invented a new, original, and ornamental Design for a Textile Fabric, of which the following is a specification, reference being had to the accompanying drawing, forming part thereof, wherein—

The figure is a plan view of a textile fabric showing my new design, with a unit of design outlined in dot and dash lines.

I claim:

The ornamental design for a textile fabric substantially as shown and described.

NATHAN TILLMAN.
